Primary Examiner — Gino Colan*Assistant Examiner* — Nicole M. Leech(74) *Attorney, Agent, or Firm* — Nixon Peabody LLP(57) **CLAIM**

The ornamental design for a gemstone as shown and described.

DESCRIPTION

FIG. 1 is a perspective view of a gemstone showing my new design;

FIG. 2 is another perspective view of the gemstone of FIG. 1;

FIG. 3 is a rear elevation view of the gemstone of FIG. 1;

FIG. 4 is a top plan view of the gemstone of FIG. 1;

FIG. 5 is a bottom plan view of the gemstone of FIG. 1;

FIG. 6 is a front elevation view of the gemstone of FIG. 1;

FIG. 7 is a left side view of the gemstone of FIG. 1; and

FIG. 8 is a right side view of the gemstone of FIG. 1.

1 Claim, 4 Drawing Sheets(56)
